UNITED STATES PATENT OFFICE.

DAVID SHULER, OF NEW DOVER, OHIO.

FLOUR-CHEST.

SPECIFICATION forming part of Letters Patent No. 324,419, dated August 18, 1885.

Application filed February 6, 1885. (No model.)

To all whom it may concern:

Be it known that I, DAVID SHULER, a citizen of the United States, residing at New Dover, in the county of Union and State of Ohio, have invented a new and useful Improvement in Flour-Chests, of which the following is a specification, reference being had to the accompanying drawings.

My invention relates to flour-chests; and it has for its object to provide a device of this character which shall be cheap and simple in its construction, and strong and durable; to provide a flour-chest with an inclined bottom, and with an improved construction of kneading-board, and lid or cover for closing said flour-chest.

With these ends in view the invention consists in the improved construction and combinations of parts hereinafter fully described, and pointed out in the claims.

In the drawings, Figure 1 is a perspective view of a flour-chest constructed in accordance with my invention. Fig. 2 is a vertical transverse section of the same. Fig. 3 is a longitudinal vertical section, and Fig. 4 is a detail view of a portion of one of the inner sides of the chest, showing the arrangement of the guide-pins and the stop pin or lug.

In the accompanying drawings, in which like letters of reference indicate corresponding parts in all the figures, A represents the frame of the chest, which is divided into two compartments, B B', by means of an inclined or slanting partition-wall, D, said wall inclining downwardly from the front of the frame to the rear thereof.

Hinged doors a are provided on the lower compartment, B', by which access may be had thereto, and on the side walls of said compartment B' are provided holes or openings, which are covered by a gauze or wire netting.

The sides of the frame A are cut off diagonally at their forward ends, and the front of the chest is open at its front side to a point on a horizontal line with the lower ends of the inclined portions of the sides.

C represents a kneading-board having the grooves or channels d upon its sides, which grooves or channels are adapted to receive pins e, extending inwardly from the inner sides of the upper compartment, B.

The kneading-board C is provided on its under side, at or near the rear corners thereof, with cleats f, which, when the kneading-board is pulled outwardly, limit its movement farther than a point necessary to allow the ready manipulation of the material thereon. 55

Stop pins or lugs g are also provided on the inner sides of the upper compartment, B, which pins or lugs are adapted to hold the inner end of the board against upward movement by bearing upon the upper rear ends of the same.

If desired, the said kneading-board may be removed or withdrawn, so that the pins on the sides of compartment B will be removed from engagement with the grooves or channels on the kneading-board, when the same may be raised to almost a perpendicular position, and then lowered into the compartment B and used as a scoop to push the flour to the rear end of the same, so that it may be readily removed when desired. 65

If desired, I might combine with the flour-chest a cupboard having shelves h, doors i, and drawers k. In this case the sides of the cupboard would be slightly extended and lap over the sides of the flour-chest, and be secured thereto by screws or equivalent fastening. 75

F represents a lid or cover, which, when access is to be had to the kneading-board, rests upon the upper or top edges of the sides and rear end of the compartment B, said lid or cover having pins i' at its rear corners, on the under side thereof. The pins on the under side of the said lid or cover F are adapted when the lid is drawn outward to strike or bear against stops m, located on the inner sides of the side walls of the frame, which prevent its further outward movement, and allow it to be lowered to cover the space between the front end of the kneading-board and the lower end of the cupboard. 85

By providing the flour-chest with an inclined bottom, when it is desired to remove the flour, the scoop may be more easily operated than if a plain bottom were employed. 95

The chest before described is simple and cheap in its construction, strong and durable, 100 and affords convenient and ready means for kneading bread, &c.

Having fully described my invention, what I claim as new, and desire to secure by Letters Patent, is—

1. The combination, with a flour-chest having lugs or pins on its inner sides, of a kneading-board having channels or grooves to receive the same, stop-pins on the chest, and stop-cleats on the under side of the kneading-board, as set forth.

2. A flour-chest comprising in its construction a frame divided into two compartments by a slanting partition-board, lugs or pins on the inner sides of the chest, a kneading-board having channels to receive the pins or lugs,

stop-pins on the chest, and stop-cleats on the under side of the kneading-board, the upper compartment of the chest being provided with inclined front sides, a lid or cover having pins at its rear corners, and stops *m* on the inner sides of the chest to engage the same, substantially as set forth.

In testimony that I claim the foregoing as my own I have hereto affixed my signature in presence of two witnesses.

DAVID SHULER.
